UNITED STATES PATENT OFFICE.

FREDERICK LORENZEN, OF CHICAGO, ILLINOIS.

COMBINATION TABLE AND PHONOGRAPH.

Application filed December 17, 1920. Serial No. 431,384.

To all whom it may concern:

Be it known that I, FREDERICK LORENZEN, of the city of Chicago, Cook County, Illinois, have invented a certain new and useful 5 Improvement in Combination Tables and Phonographs, of which the following is a specification.

This invention relates to talking machines and phonographs in general, but more particularly to those which have a rotary turntable for disk records, and which have a reproducer which floats on the record during the operation of the machine.

One object of the invention is to provide 15 an improved construction and arrangement whereby the phonograph or talking machine is movable into a storage position in a structure of any suitable character, such as a table, when the machine is not in use, and 20 so that the structure may be used for some other purpose.

To these and other useful ends, the invention consists in matters hereinafter set forth and claimed, and shown in the accompanying 25 drawings, in which:

Figure 1 is a plan of a table phonograph or talking machine embodying the principles of the invention.

Figure 2 is a front elevation of said table. 30 Figure 3 is a view similar to Figure 1, showing the closure open to bring the phonograph into view in the well provided for this purpose in the center of the table.

Figure 4 is a front elevation of said table 35 and phonograph, as shown in Figure 3, showing the turntable and reproducer in raised position.

Figure 5 is a longitudinal section on line 5—5 in Figure 7.

Figure 6 is a similar view showing the 40 phonograph in operative position.

Figure 7 is an enlarged plan of the structure with the table top removed and with certain parts shown in horizontal section.

Figure 8 is a transverse section on line 45 8—8 in Figure 7.

Figure 9 is an end elevation of the table.

Figure 10 is a detail sectional view showing 50 the movable throat in raised position to deliver the sound vibrations to the resonator.

Figure 11 is a similar view showing said throat in the lowered position which it occupies when the phonograph is stored in the table.

Figure 12 is a detail view of a lock for the

support upon which the reproducer and its tone arm and the throat are mounted.

Figure 13 is a sectional view of said lock.

Figure 14 is a detail sectional view of the friction device whereby the closure and 60 modifier for the outer end of the resonator are held in different positions.

As thus illustrated, the invention comprises a table top 1 provided with sides 2 and ends 3 and 4, together with legs 5 of 65 any suitable character. The said table is constructed with a well at its center, forming a chamber 6 having a bottom 7 and a closure 8 at the top thereof. This closure 8 is preferably rectangular in form, and is shaped to fit 70 the upper end of said well or chamber 6, being provided with hinges 9 at one end thereof, of any suitable character, so that the closure can be swung over flatwise upon the table, as shown in Figure 4, or swung back to closed 75 position as shown in Figure 1 when it is desired to use the structure as an ordinary table. Said closure is preferably provided at its free edge, on its under side, with a metal strip 10 having openings therein for 80 the dowel pins 11, and having other openings to engage the ends of the hooks or catches 12 by which the closure is retained in its closed position flush with the top surface of the table. Said dowel pins 11 are movable 85 up and down in the structure, and in a stationary transverse guide 13, being held in raised position by the springs 14 suitably applied thereto, whereby these springs are compressed by the downward movement of 90 the pins 11, which latter are in the form of rods. Thus, when the closure is unlatched or unlocked, the pins or rods 11 move upward slightly, thus giving the closure a 95 slight initial opening movement so that the hand can be inserted under the edge of the closure to pull it upward and over into its open position flatwise upon the table top. The hooks 12 are pivoted at 15 at the lower 100 ends, on the structure of the table, and face in the same direction, or toward the same side of the table, and are connected together by a rod 16 which slides in the guide 17, a compression spring 18 being interposed between this guide and one of the hooks, and a compression spring 19 being interposed 105 between the other hook and the guide 20, whereby endwise movement of said rod to pull the hooks out of engagement with the closure serves to compress said springs, and 110

the latter serve to yieldingly hold the hooks in locking engagement with the closure.

To operate said rod 16 a bent lever 21 is arranged to operate back and forth in the slot 22 in the wall 23 of the well or chamber in the center of the table, said lever being pivoted upon the under side of the table top at 24, within the record chamber 25, and provided with a handle 26 for the operation thereof. A hinged closure 27 is provided for the record chamber 25, at the end of the table, of any suitable character. The other end of the table is provided with a stationary resonator 28 provided with an inlet end 29 at one side of the said well or chamber in the table, and provided at its mouth or outer end with a folding modifier 30 which is hinged to the under side of the table top 31 and suitably connected at its lower edge to the closure 32 which is pivoted at 33 on the structure of the table. Said modifier 30 is preferably composed of two sections hinged together at their edges, and each section is preferably in the form of a frame having a screen of cloth or other material thereon, as shown in Figure 9, said modifier being entirely unfolded and disposed in a vertical plane when the closure 32 is fully open, as shown in Figure 6; but when the closure 32 is swung upward, as shown in Figure 5, the modifier or screen 30 is then folded so that the two sections thereof lie flatwise together against the under side of the table top. The side portions of the said closure 32 are each provided with a series of small openings 34 disposed on the line of a circle struck from the pivot 33, and the table structure is provided with spring pressed locking devices 35 having rounded ends to enter said openings, whereby the closure 32 and the screen or modifier 30 may be held in various positions, depending upon the loudness of tone desired for the music or the sound vibrations coming from the resonator. The closure 32 is provided with a handle 36 by which it can be forced upward or downward, the devices 35 engaging the opening 34 to hold the closure or modifier in different positions, as stated, and being so formed that they are forced back against the springs when the handle 36 is forcibly moved up or down, whereby a sort of friction arrangement is provided for holding the closure or modifier or screen in different positions, as stated. It will be seen that the lower section of the modifier or screen 30 is rigid with the closure 32, but is hinged at its upper edge to the upper section of said modifier or screen, while the said upper section is hinged at 31 to the under side of the table top, as previously explained, thus permitting the folding operation shown and described. The structure thus far described is well adapted for use as a table, as

with the three closures 8, 27 and 34 in closed position there is nothing to indicate that the table contains anything unusual, or is anything more than an ordinary table, such as those used for writing or library purposes.

The phonograph or talking machine which is normally concealed in the well or chamber 6 previously mentioned may be of any suitable known or approved character. As shown, said talking machine comprises a horizontal support 37 mounted on brackets 38 and provided on the under side thereof with a motor 39 of any suitable character, and at its top with an ordinary rotary turntable 40 to receive the flat or disk-like records. The well or chamber 6 contains a transverse wall or support 41 upon which are pivoted at each side of the chamber a pair of short arms 42 the other end of which latter are pivoted on the brackets 38 to form a parallel notch or connection or supporting means for the motor or turntable. With this arrangement the motor and turntable are movable up and down bodily, and the turntable is always level. A similar horizontal support 43 is provided for the reproducer 44 and its tone arm 45, which latter is removably coupled to the swivel 46 at the upper end of the throat 47, from which latter the sound vibrations are delivered to the previously mentioned resonator. When in raised position, as shown in Figure 6, said reproducer can be swung over to permit the needle or stylus thereof to engage the record on the turntable in the usual and well-known manner. The reproducer is thus adapted to be swung from above the turntable, as shown in Figure 5, in order to permit closing of the closure 8 above the depressed phonograph in the well-like position in the table. The long arms 48 are pivoted on the support 41, and are also pivoted on the brackets 38, and at their extreme ends are pivoted on the brackets 49 which carry the support 43 for the reproducer and tone arm. Thus the support 43 has a greater range of movement than the support 37, so that the reproducer and tone arm move up and down bodily a greater distance than the turntable and its motor, but the two supports 37 and 43 are in the same horizontal plane, as shown in Figure 6, when the turntable and its motor and the reproducer and its tone arm are in their raised or operative positions and are ready for use. When the phonograph is in storage position in the table, the parts are then in the positions shown in Figure 5, it being observed that the support 43 is some distance below the support 37, necessarily, in order to bring the top of the tone arm 45 below the plane of the closure 8 when the latter is in closed position at the top of the well or chamber in which the phonograph is stored when not in use. A spring 50, of

any suitable character, is mounted on a transverse rod 51 and arranged to press its free end against the under side of the support 43, whereby said spring serves to raise the support 43, and thereby the support 37, as soon as the closure 8 is opened. A locking device 52, of any suitable character, as shown in Figures 12 and 13, is provided on the support 43 to engage the socket 53 formed in the table structure to hold the phonograph in raised position. When the phonograph is in its raised or operative position, the throat 47 is directly opposite and preferably in engagement with the said resonator 28, as shown in Figure 10, and when the phonograph is lowered into the storage position said throat 47 then occupies the position shown in Figure 11 at the bottom of the well or chamber 6 in the center of the table. The swivel 46 permits the reproducer and its tone arm, of course, to be swung around in the usual or well-known manner, and to be removed, when such is necessary or desirable, so that the throat 47 forms an intermediate separate element between the resonator and the tone arm. When the closure 8 is pushed downward, it not only pushes the rods or dowel pins 11 down, as previously explained, but it also pushes the phonograph downward against the tension of the spring 50 whereby the raising of the closure 8 permits the spring 50 to raise the phonograph into operative position. When it is desired to store the phonograph, the lock 52 is released, and the closure 8 is then swung over upon the phonograph, and the latter is pressed downward by the final closing movement of the closure and the latter is automatically latched by means of hooks or catches 12 previously described. The supports 37 and 43 cannot rise higher than the plane or level which they occupy in Figure 6, as the brackets 49 engage the edges of the support 37, thus locking the mechanism against further outward movement, inasmuch as the support 43 moves upward much faster than the support 37 and this movement is rendered impossible, of course, as soon as the brackets 49 engage the support 37, as this precludes any further relative upward movement between the two supports.

From the foregoing it will be seen that the phonograph is movable bodily into an out-of-storage position in the table. As shown and described, the movement of the turntable and its motor bodily is for the purpose of storing the talking machine in the table and this is also the purpose of the movement of the reproducer and tone arm bodily up and down, but it will be understood that the novelty of the construction and mode of operation can be used for any suitable or desired purpose. The invention, therefore, is not limited to the exact construction shown and described and the construction and mode of operation are not limited to any particular purpose or use, the structure shown and described being illustrative of one purpose and use of the novel construction and mode of operation illustrated and explained. Also, as stated, the phonograph may be of any suitable, known or approved character, but for some reasons, and for the purpose shown and described, the phonograph is preferably so arranged that the turntable and its motor are movable up and down bodily, while the reproducer and its tone arm are movable in a similar manner but to a greater extent.

The crank 54 can be inserted through the hole 55 to wind the motor, in the ordinary manner, when the motor is in elevated position. Thus the motor cannot be wound when the phonograph or talking machine is concealed in the table, as the means for engagement with the crank 54 are not opposite the hole 55 except when the motor is raised in the manner described.

In combining a phonograph with a table, it becomes important, of course, to retain the essential requirements of a table. The top of a table must be a certain distance from the floor, and the clearance below the table must be of a certain character, and of a certain height, otherwise the piece of furniture, although resembling a table, may not be adapted for use as such. With the construction as shown and described, therefore, one object is to keep the bottom wall 7 of the storage chamber from coming too low in the structure, so that it will not interfere with the use of the piece of furniture as a real table. The top 1 is the required distance above the floor, and so is the bottom wall 7, whereby the table can be used by a person seated in front thereof in the usual or ordinary manner. If the turn-table were on the same support upon which the reproducer is mounted, it would become necessary to lower the phonograph to a greater extent in the table and the wall 7 would then be so low that it would interfere with use of the table in the desired manner. With the construction shown and described, the turn-table moves down the minimum distance necessary to get it below the cover or closure 8, so that the latter is adapted to overlie the flat horizontal top of the turn-table, and for this purpose the reproducer is necessarily laterally displaceable, as it cannot remain between the turn-table and the cover when the latter is closed. In other words, the phonograph presents a flat horizontal top to the under side of the cover 8, when the latter is closed, and this organization keeps the phonograph from hanging down too low in the table when in the stored position thereof.

The cover 8 is presented flatwise to the

top of the turntable 40, so that the latter is presented or held practically flatwise to the underside of said cover, with only slight space if any between, thus minimizing the depth of the storage position of the talking machine below the table top.

Except for the fact that a record might be left on the turntable, and that the latter usually has a center post to engage the hole 10 in the center of the record, no space is really necessary between the top of the turntable and the underside of the cover 8 of the table top. Therefore, of course, but slight space if any is necessary for this purpose. But, in any event, the reproducer is not between the cover and turntable when the machine is in the storage position thereof.

What I claim as my invention is:

20 1. The combination of a talking machine with means for the storage thereof in a structure having a table top, whereby the structure can be used as a table when the talking machine is not in use, and wherein said table top has a movable section forming a closure and said talking machine has reproducing means and a turntable for supporting a disk record thereon, characterized by this, to-wit:—that said turntable in the 25 storage position of the talking machine is presented flatwise to the underside of said movable section, when said movable section is flush with the table top, to minimize the depth of said position below the table top, with the entire machine below the plane of the bottom of said closure, and with the cover and turntable too close together to permit said reproducing means to remain in operative relation to said record, said reproducing means being movable upward to 30 an operative position above the plane of said turntable, and downward to a storage position below said plane to permit said closure to assume said flush position thereof.

45 2. A structure as specified in claim 1, comprising a movable support for said turntable, a movable support for said reproducer, a stationary support, a parallel motion connection between said stationary support and said turntable support, and a parallel motion connection between said turntable support and said reproducer support, whereby said turntable and said reproducer are always in horizontal planes 50 which are parallel with the plane of said table top.

55 3. A structure as specified in claim 1, and upper and lower links forming a paral-

lel motion connection at each side of the machine between the reproducer and the turntable.

4. A structure as specified in claim 1, wherein said reproducer must be swung laterally from above the turntable to permit said downward displacement thereof and to 60 permit said flatwise presentation of the movable section to the top of the turntable, and means to lock the reproducer in raised position.

5. A structure having a cover and a talking machine turntable so combined that the cover when closed is presented flatwise to the top of said turntable, a reproducer for said machine, and means whereby said reproducer is movable downward to a position 70 below the plane of the top of said turntable in order to permit said flatwise presentation of the cover to the turntable, said turntable having slight downward movement in horizontal position for the flatwise presentation of the cover thereto.

6. A structure as specified in claim 5, comprising a support for said turntable, and a separate movable support for said reproducer, whereby the turntable and reproducer have relative up and down motion, and said reproducer being movable laterally from above said turntable to permit the closing of said cover.

7. A table and talking machine comprising a turntable and a reproducer and movable connections between the turntable and the reproducer for relative movement thereof to bring the reproducer above the plane of the turntable for the operation of said machine and below said plane for the storage of the machine in the table.

8. A structure as specified in claim 7, comprising a flat cover forming a part of the top surface of the table and adapted by 100 reason of said relative movement for flatwise presentation to the top of said turntable, with slight space if any between, when the machine is in the storage position thereof.

9. A structure as specified in claim 7, said connections comprising a plurality of links at each side of the machine, forming a parallel motion connection for maintaining the turntable and reproducer in horizontal 105 position.

10. A structure as specified in claim 7, comprising means forming a closed well in which said machine is both operated and stored.

FREDERICK LORENZEN.
